UNITED STATES PATENT OFFICE.

ROBERT A. MOORE, OF NEW YORK, N. Y., ASSIGNOR TO THE MOORE RIFLE AND ARMS COMPANY, INC., OF NEW YORK, N. Y.

FIREARM.

1,226,566.

Specification of Letters Patent. Patented May 15, 1917.

Application filed February 1, 1916. Serial No. 75,551.

To all whom it may concern:

Be it known that I, ROBERT A. MOORE, a citizen of the United States, residing at New York, in the county of New York and State 5 of New York, have invented certain new and useful Improvements in Firearms, of which the following is a specification.

The present invention has relation to the construction of army rifles of the type employing sliding breech bolt mechanism.

The invention is designed primarily with a view to the simplifying of the breech bolt mechanism of firearms of the above class so as to reduce to a minimum the number of 15 parts employed, and also to provide a formation of such parts such as will facilitate the manufacture of the same under practical commercial conditions.

A special feature of the invention also 20 resides in the peculiar construction of the breech bolt itself and the operating and controlling means for the latter by which the bolt is held at special adjustments incidental to assuming cocked, safety, and fired positions.

Still another feature of the invention resides in the employment of peculiar adjustable stop mechanism for variably limiting the movement of the breech bolt, and likewise controlling its removability, the said 30 variable movement being utilized for the customary purpose of permitting normally sufficient movement of the breech bolt to enable unloading of the firearm, and whenever 35 the stop mechanism is so set, to enable the automatic feeding of a shell or cartridge to the receiver from the magazine of the weapon.

In addition to the foregoing the invention 40 involves other detail features of construction of the firearm including a special ejector for the spent shells, a peculiar form of bottom closure for the magazine, and other features 45 by way of details of lesser importance, all of which will be readily recognized upon reference to the detailed description herein-after, and to the accompanying drawings in which:

Figure 1 is a vertical longitudinal sectional view showing the general features of construction and arrangement of the breech bolt mechanism;

Fig. 2 is a horizontal sectional view taken 55 about on the line 2-2 of Fig. 1;

Fig. 3 is a detail perspective view of the firing pin handle.

Fig. 4 is a sectional view taken about on the line 4-4 of Fig. 2.

Fig. 5 is a detail perspective view of the breech bolt and associated parts directly carried thereby.

Fig. 6 is a fragmentary sectional view showing the locking sleeve in rear end elevation.

Fig. 7 is a plan view showing more clearly 65 the formation of the recesses in the locking sleeve.

Fig. 8 is a detail perspective view of the lug carried by the firing pin handle.

In the drawings 1 designates the barrel 70 of the rifle and 2 the usual receiver located at the breech end of the barrel and provided at its side with the slot 3 through which the spent cartridge passes when ejected. At its top the receiver 2 has a slot 4 through 75 which the operator introduces fresh cartridges one at a time into the breech, ready to be carried forward into the barrel by the subsequent forward movement of the breech bolt 5 which slides longitudinally in the receiver 2 in the well known manner. Beneath the receiver 2 is located the magazine 6 adapted to receive a clip of fresh shells or cartridges which are adapted to be fed upward into the receiver 2 by the usual spring 80 85 7. The bottom of the magazine 6 is formed by means of a closure plate 8 pivoted at 9 to the frame of the breech bolt mechanism and adapted to swing laterally or in approximately a horizontal plane. The rear end of the closure plate 8 is notched and adapted to be engaged by a vertically swinging pivoted catch 10 which locks the plate in its closed position and must be disengaged therefrom to permit of lateral opening 90 95 95

movement of the plate.

The breech bolt 5 is formed at one side with the kerf 11 at the front end of which is located the ejector 12. The ejector 12 is mounted in a recess in the bolt 5 and maintained from displacement by the cross pin 13. Said ejector has a projection 12' extending into the kerf 11. Opposite to the ejector 12, the bolt 5 has the extractor 14 of any conventional construction.

The firing pin 15 is mounted to slide into the bolt 5 and its rear extremity is reduced and threaded to receive thereon the handle 17. Encircling the firing pin 15 is the coil spring 16 which acts to impinge the pin 110 against the percussion cap of the shell in the usual way. The handle 17 is a part of

- a handle member of hollow formation, which handle member has the fixed catch 18 at its lowermost portion, see Fig. 3, said catch coacting with the trigger sear 19 to hold the firing pin in firing or cocked position. The trigger 20 operates the sear 19 in an obvious manner. At its rear end the bolt 5 carries a tubular extension 5^a adapted to operate in the hollow portion of the handle 17 and screwed into the bolt. A locking cylinder 21 is mounted on the member 5^a intermediate the parts 5 and 17, is thus rotatively supported and has locking lugs 23 adapted to engage with locking recesses 25 in the breech cylinder 24. The locking sleeve 21 has the operating lever 22 for rotating it and for moving the breech bolt 5 into open and closed position, and otherwise manipulating said bolt. The bolt action incident to the operation of the lever 22, broadly speaking, is that commonly employed, a forward movement of the lever 22 when upraised shifting the fresh cartridge into the barrel at the breech and a downward movement of the lever rotating the sleeve 21 lockingly engaging the lugs 23 in the recesses 25 of the cylinder 24, under which condition the firearm is ready to be fired.
- 30 When the bolt 5 is drawn rearward carrying with it the handle 17, and subsequently returned to closed position, the lug 18 is engaged by the sear 19 and the member 17 with the firing pin 15 restrained and locked in cocked position.
- 35 In Figs. 1 and 2 the breech bolt is shown in full lines in the position illustrating the parts after the firing of the cartridge. Peculiar means is employed to hold the lever 22 in three adjusted positions in relation to the breech bolt and involves the provision of recesses 21^a, 21^b and 21^c on the rear end of the locking sleeve 21. With the parts in the position shown in Figs. 1 and 2, the 40 lever 22 is at the lower limit of its movement with the breech closed, and the locking projection 18^a seen in Fig. 3 is engaged with the recess 21^a of the member 21. The recess 21^a, see Figs. 6 and 7, has an inclined 45 wall forming a cam of gradual inclination, and is sufficiently deep that when the projection 18^a enters said recess it is possible for the firing extremity of the pin 15 to engage the cap of the shell to be fired. By 50 a preliminary upward movement of the lever 22 after firing of the weapon, which causes the engagement of the projection 18^a in the recess 21^a, the member 17 is cammed rearward with the firing pin until the projection 18^a is seated in the recess 21^b of sleeve 21. The recesses 21^b and 21^c of the sleeve are more shallow than the recess 21^a and the recess 21^b in co-operation with the projection 18^a affords a lock holding the 55 lever 22 and the breech bolt, after partial 60 lever 22 upward from the intermediate safety locked position above described is resisted materially owing to the sharp inclination of the cam of one wall of said recess 21^b. This resistance formation of the cam is purposely provided so as to make necessary the exertion of considerable pressure upward on the lever 22 in order to shift the lever beyond the safety position. Such pressure when exerted, however, will be sufficient to carry the lever up far enough to rotate the sleeve 21 until the projection 18^a engages in the recess 21^c which establishes a positive lock between the parts necessitating a rearward movement of the lever 22 and firing pin, and cocking of the firearm by engagement between the parts 18, 19 before the lever 22 may be restored to its normal position with the breech bolt at closed adjustment.
- 65 In addition to the above described coaction between the parts 18^a and the recess 21^c, it is obvious that these portions of the construction of the sleeve 21 and handle or hammer 17 afford an interlocking connection which comes into play when the lever 22 is being pulled back to cause ejection of a spent shell, the result being that the parts 17 and 21 are maintained in proper relative positions so as to insure that the locking lugs 23 on the sleeve 21 will not be disturbed so far as any possibility of disalignment of these parts with their locking recesses 25 is concerned. In other words, the interlock established between the projection 18^a and the recess 21^c keeps the parts 17 and 21 in proper relative positions when the breech block is thrown back and the member 21 otherwise free to shift rotatably on the part 5^a.
- 70 To assume the safety position after the weapon is loaded, it is only necessary to pull the trigger 20, raise the lever 22 to its intermediate safety adjustment, and permit the released handle 17 and firing pin to move forward to the safety position wherein the member 18^a engages in the recess 21^b.
- 75 For the purpose of variably limiting the movement of the bolt 5 whereby lesser movement of the same may be controlled for the unloading of the firearm through the slot 4, and a greater movement of the bolt permitted to permit its front end to clear the magazine 6 and afford automatic loading of the gun, special stop means are employed. Referring to Figs. 2 and 4 especially, said stop 80

means will be seen to consist of the rotative stops 26 and 26^a, the ends of which are adapted to engage in the kerf 11 and each of said ends by abutment with the ejector 12 will limit the rearward opening movement of the breech bolt. The stops 26 and 26^a are threaded at 27 and adapted to be turned to screw in and out for cooperation with the ejector 12, (and thus with the bolt 5) by means of suitable thumb pieces 28. When the stop 26^a is in the position shown in Fig. 2 in full lines, the bolt 5 is limited so as to permit hand loading only, through the slot 4. By turning the member 28 of the stop 26^a to a vertical position (see dotted lines) the inner end of the stop is withdrawn from the kerf 11 and the stop 26 comes into play to permit additional movement of the bolt 5 so that automatic loading from the magazine 6 is obtained. In the latter adjustment stop 26 engages the ejector 12, of course. If desired to withdraw the bolt 5 entirely from the breech of the weapon, the thumb piece 28 of the stop 26 is turned up causing outward movement of the stop, and if the stop 26^a has likewise been previously so adjusted, the bolt 5 is free to be removed endwise in the usual way. Each member 28 has a spring pressed pin α to enter a recess in the breech 30 and hold the stop against unauthorized movement. When desired to set the gun for magazine feed action the thumb-piece 28 of the stop 26^a will be turned a half revolution to cause its pin α to engage a recess in the outer end of the stop 26.

The lug 18 on the member 17 is preferably detachably connected thereto having a dovetail portion 18^b adapted to be driven into a correspondingly shaped groove in the member 17 and the lug thus frictionally held in position. The lug 18 has a tongue 18^c engaging in a groove in the underside of the tubular extension 5^a of the bolt 5, see Figs. 6 and 8. This tongue prevents turning of the member 17 relatively to the extension 5^a.

The member 26 performs the triple function of engaging and actuating the ejector 12 for effecting ejecting movement of the latter, to variably limit the movement of the breech bolt 5 and to control the detachability of the breech bolt and connected parts from the breech of the weapon.

By reason of the extreme simplicity of the construction of the various parts of the invention they may be very readily manufactured, at a minimum degree of cost and with due allowance for full efficiency in practical operation.

Having thus described my invention, what I claim as new is:

1. In a firearm, breech mechanism comprising in combination, a receiver, a breech bolt operating therein, a firing pin and its operating means carried by said bolt, trigger controlled catch mechanism for said pin,

an operating and locking lever for said bolt, and means intermediate the lever and the firing pin coöperative to hold the lever in a position maintaining the bolt in closed position with the firing pin operative, a second position in which the firing pin is held inoperative, and a third position in which the lever is locked against direct return to normal.

2. In a firearm, breech mechanism comprising in combination, a receiver, a breech bolt operating therein, a firing pin and its operating means carried by said bolt, trigger controlled catch mechanism for said pin, an operating and locking lever for said bolt, and means intermediate the lever and the firing pin coöperative to hold the lever in a position maintaining the bolt in closed position with the firing pin operative, and a second position in which the firing pin is held inoperative, and to lock the lever whereby to compel cocking movement of the firing pin previous to return of the lever to normal.

3. In a firearm, breech mechanism comprising in combination, a receiver, a breech bolt operating therein, a firing pin and its operating means carried by said bolt, a handle member on the firing pin, a locking sleeve on the bolt provided with an operating lever, trigger mechanism, a trigger catch on said handle member, an interlocking means intermediate the handle member and sleeve for holding the sleeve and lever against unauthorized movement at normal position with the breech closed, and also, in a position rendering the firing pin inoperative and to lock the sleeve and lever so as to compel cocking movement of the firing pin prior to return of the sleeve to normal.

4. In breech mechanism for firearms, the combination with a sliding breech-bolt, of means for variably limiting the movement of the said bolt comprising spaced stops having portions adapted to coact with the bolt, actuating members coöperative with said stops to shift the same for said coaction, and coacting means between said actuating members for maintaining them in predetermined relation.

5. In breech mechanism for firearms, the combination with a sliding breech-bolt, of means for variably limiting the movement of the said bolt comprising rotative stops having portions adapted to coact with the bolt to variably limit its movement, a thumb-piece for actuating each stop, and means intermediate the thumb-pieces to hold the stops against unauthorized movement.

6. In breech mechanism for firearms, the combination with a sliding breech bolt, of a receiver in which the bolt operates, and means to detachably connect the bolt with and to limit its movement in the receiver including stops movable inwardly and out-

wardly and adapted to stop movement of the bolt, an actuating member to move each stop into and out of coöperation with respect to the bolt, and means to positively hold each actuating member against unauthorized movement.

7. In breech mechanism for firearms, the combination with a sliding breech-bolt, of a receiver in which the bolt operates, and means to detachably connect the bolt with and to limit its movement in the receiver including spaced stops coöoperative with the

bolt to variably limit its movement, thumb-pieces for moving the stops to cause either to coact with the bolt, and to shift the stops out of coöperation with the bolt, to variably limit movement and to permit removal, respectively, of said bolt, and means to hold said actuating members against unauthorized movement including a detent on one thumb-piece coöoperative with the other thumb-piece.

In testimony whereof I affix my signature.
ROBERT A. MOORE.
